CLAIM

We claim the ornamental design for a control box for digital signage, as shown and described.

DESCRIPTION

FIG. 1 is a front perspective view of a control box for digital signage showing a new design;

FIG. 2 is a rear perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view showing a control box for digital signage in an environment of use.

The dot-dot-dash lines in FIG. 9 illustrate the border of the view and form no part of the claimed design. The broken lines represent portions of the control box for digital signage that forms no part of the claimed design. The broken lines of the signage display in FIG. 9 are for environment purpose only and form no part of the claimed design.

1 Claim, 9 Drawing Sheets
